UNITED STATES PATENT OFFICE.

WILLIAM DUPUIS, OF POLSON, MONTANA.

CUFF LINK.

Application filed April 7, 1925. Serial No. 21,337.

To all whom it may concern:

Be it known that I, WILLIAM DUPUIS, a citizen of the United States, residing at Polson, in the county of Lake and State of Montana, have invented certain new and useful Improvements in Cuff Links, of which the following is a specification.

This invention relates to a cuff link, and has for its object to provide, in a manner as hereinafter set forth, a new, original and novel article of the class referred to, having an elastic element tending to normally maintain the buttons of the link in close opposed relation when they are connected to the cuff and to provide for convenient passage of the hand through the cuff or the expeditious removal of the cuff over the hand when the link is attached to the cuff.

Further objects of the invention are to provide, in a manner as hereinafter set forth, a cuff link, which is simple in its construction and arrangement, strong, durable compact, thoroughly efficient and convenient in its use, readily assembled, and inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:—

Figure 1 is an elevation of a soft or "French" cuff, showing the adaptation therewith of a link, in accordance with this invention.

Figure 2 is a plan view of the link prior to the bending of the coupling member between the buttons to form the elastic element.

Figure 3 is an edge view of the link shown in Figure 2.

Figure 4 is an elevation of a cuff link, in accordance with this invention.

Figure 5 is a plan view thereof.

Referring to the drawings in detail, 1 and 2 denote a pair of buttons which can be of any shape or design desired, and secured to the inner face of each button is a diametrically disposed yoke 3 of the desired width.

Each of the arms of the yoke is laterally flanged, as at 4, and fixedly secured in any suitable manner to the inner face of the button. The yoke 3 is extended from the inner face of the button and is adapted to have hinged or pivoted therewith one end of an elastic element to be presently referred to.

The elastic element is referred to generally by the reference character 5 and is constructed from a spring metal strap 5', having each end terminal portion thereof enlarged, as at 6, and formed with a pair of spaced bendable projections 7, which are bent around the yoke 3, as illustrated in Figure 5 so as to provide in connection with the yoke 3 a hinge or pivot connection between one end of the element 5 and a button.

The metallic strip from which the elastic element 5 is formed is bent in W shape but with the inner arms 8, 9 of the element 5 of greater length than the outer arms 10, 11. The upper ends of the arms 8 and 9 merge into each other. The lower end of the arm 8 merges into the lower end of the arm 10, and the lower end of the arm 9 merges into the lower end of the arm 11. The extensions are formed on the upper ends of the arms 10 and 11.

In providing the elastic element 5 of W shape, and with the arms set up in the manner as referred to, the element 5 normally tends to maintain the buttons 1 and 2 in close opposed relation, and further provides for the extending of the element to shift the buttons 1 and 2 away from each other when pressure is applied to the cuff 12 when passing the hand through the cuff, under such conditions the link can be attached to the cuff before the same is positioned on the wrist of the wearer, as element 5 permits of the positioning and removal of the cuff expeditiously when occasion requires.

It is thought that the many advantages of a cuff link, in accordance with this invention, can be readily understood, and although the preferred embodiment of the invention is as illustrated and described, yet it is to be understood that changes in the details of construction can be had which will fall within the scope of the invention as claimed.

What I claim is:—

1. A cuff link comprising a pair of buttons, and a W shaped elastic element arranged between and having each end pivotally connected to one of said buttons, the inner arms of said element opposing each

other throughout, of greater length than the outer arms thereof and each merging into one end of an outer arm, the said ends of the outer arms opposing each other.

5 2. A cuff link comprising a pair of buttons each having its inner face provided with a yoke, an elastic element arranged between said buttons, said element formed from a folded flat strip of spring metal and having each end thereof provided with a pair of spaced extensions bent around a yoke to pivotally connect the end with a button.

15 3. A cuff link comprising a pair of buttons each having its inner face provided with a yoke, an elastic element arranged between said buttons, said element formed from a folded flat strip of spring metal and having each end thereof provided with a pair of spaced extensions bent around a yoke to pivotally connect the end with a button.

20 yoke to pivotally connect the end with a button, said element being W shaped in contour, having its inner arms opposing

each other throughout and of greater length than the end arms thereof.

4. A cuff link comprising a pair of buttons each having its inner face provided centrally thereof with a yoke, an elastic element arranged between said buttons and formed from a folded flat strip of spring metal to provide a pair of inner and a pair of outer arms, the inner arms of said element opposing each other throughout, of greater length than the outer arms thereof and each merging into one end of an outer arm, the said ends of the outer arms opposing each other, each of said outer arms having its other end formed of a pair of spaced extensions angularly disposed with respect to the remaining portion of said arm and bent around a yoke to pivotally connect such arm with a button.

35 30 40 In testimony whereof, I affix my signature hereto.

WILLIAM DUPUIS
